UNITED STATES PATENT OFFICE.

HENRY B. SARGENT, OF NEW HAVEN, CONNECTICUT, ASSIGNOR TO SARGENT & COMPANY, OF NEW HAVEN, CONNECTICUT, A CORPORATION OF CONNECTICUT.

SPRING-HINGE.

SPECIFICATION forming part of Letters Patent No. 727,697, dated May 12, 1903.

Application filed October 21, 1898. Serial No. 694,204. (No model.)

To all whom it may concern:

Be it known that I, HENRY B. SARGENT, of the city and county of New Haven, in the State of Connecticut, have invented new and useful Improvements in Spring-Hinges, of which the following is a full, clear, and exact description, when taken in connection with the accompanying drawings, which form a part thereof, and in which—

10 Figure 1 represents a front elevation of a spring-hinge embodying my invention; Fig. 2, a view, partly in vertical section, partly in elevation, of one of the barrels of the hinge; Figs. 3 and 4, horizontal sections on lines 3 3 15 of Fig. 1, the outer leaves of the hinge being shown in different positions and Fig. 4 showing a modification of the central leaf.

In all figures similar letters of reference represent like parts.

20 This invention relates to wrought-metal spring-hinges, and more particularly to that class of spring-hinges known as "double-acting," whereby the door to which it is attached is enabled to swing in two directions.

25 The invention consists in the various improvements in the construction of the hinge, as more particularly set forth hereinafter, whereby a simpler, more efficient, and durable hinge is provided.

30 Referring to the drawings, the parts designated by the letter A represent the two outer leaves of a spring-hinge, which are adapted to be secured to the door and door-frame by screws through screw-holes a, while the part

35 B represents the central leaf of the hinge, which is formed integral with the two spring-containing barrels C and C' in the following manner: A single blank of sheet metal extends, as shown in cross-section in Figs. 3 and

40 4, from a point b' toward the barrel C, forming the portion b and the barrel C. The blank extends back from the barrel C, parallel and contiguous to the portion b, forming a second thickness or web b² of the central leaf. At the opposite end of the leaf the blank forms the second barrel C' and extends

45 to and terminates at the point b', where the portion b begins, forming the portion b³ of the central leaf, parallel and contiguous to the portion b² and on the same line with the

portion b, with which it makes a single thickness of metal. By this construction the central leaf is formed integral with the two barrels and consists only of two thicknesses of metal. The one thickness or web b² is continuous and integral with the barrels C and C', while the other web is formed of the two end portions b and b³, which extend from the barrels and terminate on the same straight line on the same side of the web at the point b', which is shown herein at substantially the middle of the central leaf, but may obviously be at the most convenient point.

If for any particular class of work it is desirable to increase the strength of the central leaf, a reinforcing-plate D, as shown in cross-section, Fig. 4, is placed over the meeting ends of the blank forming the leaf and barrel portions and riveted to the central leaf.

Within the barrels C and C' are located 70 helical springs, which may be of the double form shown in Fig. 2, wherein a smaller or interior spring E is included within a larger or exterior spring E'. At the two ends of the springs E and E' are spring-holders F and F', 75 to which the springs are rigidly secured, the spring-holder F' being fitted into and rigidly secured by studs or other means in the end of the barrel, while the other, F, extends into the barrel, but is free to rotate independent thereof. The spring-holder F is of equal diameter with the barrel and is provided with radially-extending holes f' for a stop-pin G and a reduced portion, which forms with the body of the holder a shoulder f, adapted to be 80 seated on the upper edge of the barrel. Both spring-holders F and F' are provided with double annular recesses f² and f³ for the ends of the spring. By this construction one end of the spring is held rigid with the barrel, 90 while the other end is capable of being turned independent of the barrel by the movable spring-holder F, which in turn is rigidly connected to the outer leaf A by having the stop-pin G bear against the inner edge a' of the 95 outer leaf or leaves, as shown in Fig. 1.

The connection between the outer leaves A and the central leaf C is as follows: The outer leaves A are provided at their upper and lower edges with flanges a³, bent at right an-

gles to the plane of the leaves and which are prolonged beyond the inner edges of the leaves to form bearings a^4 for the pintle or pintles H, which extend through said bearings, as shown hereinafter, and through axial perforations f^4 in the spring-holders. Between the bearings a^4 of the outer leaves A and the spring-holders F and F', which close the ends of the barrels C and C', are interposed washers K, consisting of inner cores k , of steel or other metal, and an outer covering k' , of wrought metal, Fig. 2. As the spring-holders F and F' are also formed of steel, the bearing-surfaces of the washers K and spring-holders are of hard metal. In the washers K are axial perforations k^2 for hollow sleeves L, which project through and beyond the bearings a^4 of the outer leaves. Beyond the bearings a^4 the sleeves L have annular flanges l , adapted to fit against the outer faces of the bearings a^4 , while the lower ends of the sleeves are turned upward to bind by frictional contact the washers K. By this means the washers K are bound to the bearings a^4 of the leaves A to rotate therewith and independent of the barrels C and C', while a hard-metal bearing is provided for the meeting surfaces of the parts which rotate thus independent of each other.

The outer ends of the sleeves L are externally screw-threaded, as shown at l' , for the detachable caps M, which are correspondingly internally threaded. Hollow washers N are fitted over the annular flanges l between the caps M and the bearings a^4 . The pintles H, which extend through the barrels and spring-holders, also project through the sleeves L and have their ends spun down on the outer end of the sleeves L, as shown at h in Fig. 2, so that they will rotate with the sleeves and with the outer leaves A.

The leaves A are provided with short studs O

on their inner surfaces, which when the hinge is closed (or, in other words, the outer leaves folded on the central leaf by the springs) are adapted to abut against the central leaf B, Fig. 3, to hold the outer leaves A in a position parallel to each other and to the central leaf. Therefore when the hinge is secured in place the door and jamb will be in proper position relative to each other for the most efficient operation of the hinge.

Having described the invention, which may vary somewhat in construction without departing from the spirit thereof, what I claim, and desire to secure by Letters Patent, is—

1. In a spring-hinge, the combination with the spring-containing barrel; of hard-metal spring-holders closing the ends of the barrel; a leaf having flanged bearings extending at right angles thereto; hard-metal washers between said bearings and spring-holders; sleeves extending through said bearings and washers and provided with flanges to bind the same together by frictional contact; caps adapted to be screwed onto the outer ends of said sleeves; and pintles extending through said barrel, spring-holders and sleeves into said caps, substantially as described.

2. In a double-acting spring-hinge, the combination with a central leaf; of two outer leaves; suitably-located springs normally tending to fold the outer leaves upon the central leaf; and stops on the said outer leaves adapted to abut against said inner leaf to hold said leaves in a position parallel to each other when folded, substantially as described.

In witness whereof I have hereunto set my hand this 13th day of October, A. D. 1898.

HENRY B. SARGENT.
